(57) **CLAIM**

The ornamental design for a bottle lid, as shown and described.

DESCRIPTION

FIG. 1 is a top front right side perspective view of a bottle lid in a closed configuration, showing our new design; FIG. 2 is a bottom rear left side perspective view thereof in the closed configuration;

FIG. 3 is a front elevation view thereof in the closed configuration;

FIG. 4 is a rear elevation view thereof in the closed configuration;

FIG. 5 is a left side elevation view thereof in the closed configuration;

FIG. 6 is a right side elevation view thereof in the closed configuration;

FIG. 7 is a top plan view thereof in the closed configuration; FIG. 8 is a bottom plan view thereof in the closed configuration;

FIG. 9 is a top front right side perspective view thereof in an open configuration;

FIG. 10 is a bottom rear left side perspective view thereof in the open configuration;

FIG. 11 is a front elevation view thereof in the open configuration;

FIG. 12 is a rear elevation view thereof in the open configuration;

FIG. 13 is a left side elevation view thereof in the open configuration;

FIG. 14 is a right side elevation view thereof in the open configuration;

FIG. 15 is a top plan view thereof in the open configuration; and,

FIG. 16 is a bottom plan view thereof in the open configuration.

(Continued)

The broken lines shown in the figures depict portions of the bottle lid that form no part of the claimed design.
